(57) **CLAIM**

We claim the ornamental design for a monitor arm, as shown and described.

DESCRIPTION

FIG. 1 is a top front right perspective view of a monitor arm, showing our new design;

FIG. 2 is a top rear left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken away bracket symbols with evenly spaced broken lines in the drawings indicate that any portion of the article beyond what is shown forms no part of the claimed design. The dash-dot broken lines represent the bounds of the claimed design, and form no part of the claimed design. The evenly spaced broken lines are directed to environment and form no part of the claimed design.
